UNITED STATES PATENT OFFICE.

WILLIAM EDGAR ZOLMAN AND ANDREW W. BRADSHAW, OF FARMINGTON, MISSOURI.

BOLD-FACED-SLUG-CASTING ATTACHMENT FOR LINOTYPE MACHINES.

Application filed August 26, 1922. Serial No. 584,476.

To all whom it may concern:

Be it known that we, WILLIAM EDGAR ZOLMAN and ANDREW W. BRADSHAW, citizens of the United States, residing at Farmington, in the county of St. Francois and State of Missouri, have invented certain new and useful Improvements in Bold-Faced-Slug-Casting Attachments for Linotype Machines, of which the following is a specification, reference being had to the accompanying drawings.

This invention relates to type casting machines, such as the linotype machines described in the Mergenthaler patents, Nos. 436,531 and 436,532, and particularly to means for bringing the line of matrices into proper relation to the mold so that bold-faced slugs may be cast from matrices assembled in light faced position in the assembler of the type setting machine.

In linotype or intertype machines of this character the line of matrices composed upon the assembler is shifted to the casting mechanism by a carrier commonly known as the first elevator, and the purpose of the present invention is to vary the movement of the carrier in bringing the line into proper relation to the mold to thus cause the alignment of any matrix for bold faced cast or type that will align for the light faced cast. In linotype machines as now on the market this is impossible from worn matrices.

A further object is to provide an attachment adapted to be applied beneath the elevator cap which may be interposed between the adjusting screws of the elevator cap and the vise to thus prevent the elevator cap from descending as far as it ordinarily would descend, which attachment may be readily shifted out of such interposing position, and which attachment also includes an automatic safety pin which prevents the line of matrices from being shifted into operative position on the elevator cap if the mats are thoughtlessly or carelessly assembled on the upper rail of the assembler instead of on the lower rail of the assembler when the attachment is thrown in use, this safety pin thus preventing any loss of time from a "squirt" that is sure to follow such neglect or carelessness.

Another object is to provide an attachment of this character which will cause the matrices to be assembled on the fiber buffer of the assembling elevator, which thus very

materially reduces the wear to the lower back lug of the matrix.

Still another object is to provide an attachment to the elevator operating cam which shall increase the throw of the elevator operating cam and thus give increased motion to the elevator in its lift for alignment of matrices.

A further object is to provide a spring associated with the first elevator lever which is slightly weaker than the one now in use to accommodate the extra action of the elevator occasioned by the necessity of using the shoe on the cam previously referred to in the ordinary action of casting light face slugs.

These objects will appear more fully in the accompanying specification.

Our invention is illustrated in the accompanying drawings, wherein:

Figure 1 is a fragmentary front elevation of a linotype machine showing the parts to which our improvement is to be applied;

Figure 2 is a side elevation of the same, showing the heel b applied to the cam B;

Figure 3 is a perspective view of the first elevator and vise showing our improvement applied thereto;

Figure 4 is a fragmentary sectional view from front to rear of the first elevator cap, the vise and the mold, showing the device in operative position;

Figure 5 is a fragmentary perspective view of the assembler, showing the means on the assembler ordinarily used for elevating the slugs to a bold-faced position;

Figure 6 is a fragmentary plan view looking upward toward the under side of the first elevator cap and showing in full lines our device in applied position and in dotted lines the device folded and out of the way;

Figure 7 is a longitudinal sectional view of the controlling spring link K modified to operate with our attachment;

Figure 8 is a side elevation of the cam B, showing the heel applied thereto;

Figure 9 is a sectional view on the line 9—9 of Figure 8;

Figure 10 is a perspective view of our attachment with the bracket separated from the remainder of the parts.

In these drawings, we have illustrated so much of a standard linotype machine as is necessary for an understanding of our invention, and in these drawings A designates the base of the machine, 'B' the

- main operating cam which operates the elevator, C the elevator itself, D the elevator cap, E the oppositely disposed rails of the elevator cap and in which the matrices X 5 slide, F designates the vise cap, G the stop screw carried by the elevator, H the rod or "automatic" which controls the clutch mechanism, and I the screw which normally engages this rod to actuate it. In ordinary 10 circumstances and with matrices having plain faced type of ordinary font, the elevator C descends until the stop screw G contacts directly with the vise cap F and the screw I with the rod E. The elevator is 15 operatively connected by a link K to a lever L which is operatively controlled, as usual, by the cam B. The matrices are assembled, as usual, upon either the upper rail or the lower rail of an assembler or 20 assembling block M. The type are shifted from the assembler onto the rails E of the elevator cap in the usual manner. All these parts are such as are ordinarily found in linotype or intertype machines and may be 25 of any standard or ordinary construction.
- Our attachment comprises an angular bracket 10 which is attached to the side wall of the elevator cap D, and pivoted to this bracket is a relatively thick rod or finger 11 30 which is pivoted intermediate its ends but adjacent one end and which is adapted to be swung so as to carry the extremity of the long arm of the finger beneath the adjusting screw G, the short arm of this finger 11 35 constituting a handle projecting beyond the bracket 10 and forming means whereby this finger may be shifted from the dotted line position shown in Figure 6 to its full line position and vice versa.
- Attached to the finger 11 and extending approximately parallel thereto is a finger 12, the end of which is provided with a thickened portion 13, this finger being attached to the finger 11 by means of a screw 40 14 and being provided with flanges 15 which embrace the finger 11. The thickened portion 13 at the extremity of the finger 12 is interposed between the adjusting screw I and the pin at the upper extremity. 45 of the clutch operating rod H when the finger 11 has its extremity interposed beneath the adjusting screw G and the upper face of the vise F. When the finger 11 is swung to the dotted line position in Figure 6, the finger 12, of course, also moves to the dotted line position in Figure 6 and both fingers 50 are actuated by the finger 11.
- Pivoted in a recess in the end face of the finger 11 is a flat metal rod 16 which carries at its extremity a pivoted pin 17 which 55 is pivoted for movement in a plane parallel to the plane of movement of the rod 16 and which passes through an opening in the side wall of the rail E. When the parts are 60 shifted to their operative position, as shown

in full lines in Figure 6, this pin 17 projects into such position as to block or stop matrices from entering the elevator if these matrices are carelessly assembled on the upper rail M of the assembler. This pin prevents the machine from operating if the matrices are thoughtlessly or carelessly assembled on the upper rail of the assembler when the attachment is thrown in use. This 70 prevents any possible damage to the matrices so assembled and prevents loss of time from the "squirt" which would otherwise be sure to follow such neglect. A stop 75 10⁴ is formed on the bracket 10 to prevent arm 12 when out of use getting in the way 80 of the elevator on downward stroke.

It will be understood by those acquainted with type setting machines of this character that this attachment causes and requires that the matrices, in order that the machine 85 may operate properly, shall be assembled on the fiber buffer of the assembling elevator and this very materially reduces the wear on the lower back lug of each matrix. The 90 interposition of the fingers 11 and 12 requires that a higher lift for alignment be given to the elevator in order to bring the matrices into proper position when casting "bold face," and means must be provided for giving this increased motion to the elevator to align the matrices. To this end, we 95 provide a shoe 18 which is adapted to be attached to and fit against the rounded face of the heel b of the elevator cam B. Shoe 100 18 consists of a strip of metal having a width slightly greater than that of the heel of the cam and curved to fit against the heel, one end of the strip being thinned down so as to merge into the edge contour of the cam, this strip being held to the cam by 105 means of a plurality of integral yokes or lugs 19 which extend upward on each side of the cam beyond the cut-out at the heel of the cam, each pair of lugs or yokes being apertured for the passage of a transverse cross bar 20 through which passes a square-headed adjusting screw 21 which binds against the inner face of the heel of the cam, as illustrated clearly in Figure 9, and draws the shoe 18 into close contact with the heel of the cam and holds it firmly in place. This shoe 18 increases the throw of the cam at its heel and thus increases the 110 motion of the elevator in its "lift for alignment" of matrices.

In view of the increased motion given to the elevator, it is necessary to provide for this increased motion at the link K. This link K, as illustrated in Figure 7, has the usual form of the ordinary link and is formed of a cylindrical member enclosing a coiled spring 22. This spring abuts against the upper end b of the link but bears at its lower end against a head 23 which is enclosed within the cylindrical casing K, this 115 120 125 130

head 23 supporting the lower end of the spring and having a screw-threaded aperture to engage the screw-threaded end of the adjusting I-bolt 24. This I-bolt connects 5 with the end of the first elevator lever L in the usual manner, which elevator lever L is operated by the cam B, as usual. The spring 22, it will be noted, is of the same construction as that ordinarily used but is somewhat 10 weaker than the one now in use in order to permit the extra lift for alignment when light face type is being cast, the elevator having its full downward stroke. The spring 22 takes care of the extra action of the first 15 elevator lever. When the elevator is in casting position, the lugs of the line of matrices are in the groove of the mold N which is carried, as usual, on the rotatable mold wheel O. The lever under the action of the 20 cam acts to lift the elevator to align the matrices, and under these circumstances the spring acts as a cushion.

In casting bold faced slugs from type assembled on the upper rail of the assembler 25 and delivered to the upper rail of the elevator jaw, if worn mats are used the mats will not align properly and a zigzag line will result, due to the fact that some mats will be worn more than others. These mats are 30 ordinarily worn on a lower corner, this being the point engaged by the elevator jaw to align the mats with a mold slot for bold faced cast. The wear of this part of the mat occurs in ordinary assembling, especially 35 where the mats are assembled on the upper rail, which is of metal. For the light face line, mats are assembled on the lower rail of the assembler on a fiber buffer and delivered to the lower position on the elevator 40 jaw where they hang by both upper lugs. These upper lugs of the mats never wear at the point of hang and, therefore, the mats when assembled will never produce zigzag 45 light faces when handled correctly by the machine. Where my invention is in use, the mats are assembled as for light face, and therefore, delivered to the lower position on the elevator jaw where they hang on the upper lug instead of resting on the lower lug 50 when assembled for bold faced casting. The downward stroke of the elevator to casting position is stopped by member 11 so that the lugs of the mats enter into the upper grooves of the mold, the position for bold faced casting. The part 11 holds the elevator up instead of the mats being held up in the elevator to secure this bold faced position.

In the ordinary action of the elevator 60 having its full downward stroke, after the mat lugs have entered the groove of the mold there takes place an action for aligning the mats before the cast is made. This

alignment is accomplished by the slightly raised portion or heel of the cam B. Now 65 with the elevator up by reason of the use of the member 11 or interponent, this "lift for alignment" is so very small that type faces on the slug are untrue, hence the necessity of providing the extra shoe or plate 70 18 for the heel of the cam. This provides the necessary "lift for alignment" action when the elevator is held up by member 11. The slightly weaker spring 22 on the connecting link is necessary because of this extra lift 75 occasioned by the shoe 18 only in the ordinary casting of light face when elevator has full downward stroke.

We claim:

1. A bold-faced slug casting attachment 80 for linotypes comprising a bracket adapted to be attached to the side wall of the elevator cap on a level with the lower edge of said side wall, a lever pivoted adjacent one end to the bracket, the short arm of the lever constituting a handle projecting beyond the bracket and the extremity of the long arm being adapted to be disposed beneath the elevator cap and in alignment with the stop screw of the elevator cap, a finger 90 attached to the lever and extending parallel thereto but terminating short of the end of said member and having at its extremity a thickened portion adapted to be disposed immediately beneath and registering with the clutch operating screw of the cap, an arm carried by the member and projecting at an angle thereto, and a pin pivoted on said arm and adapted to extend through the side wall of the elevator cap and to be projected into the path of movement of the matrices if assembled on the upper rail when the lever and finger are disposed with their ends directly beneath said screws.

2. In a machine for casting type lines, a 105 mold, an elevator having variable movement in relation thereto, means shiftable into position to limit the downward movement on the elevator and shiftable out of such position, a lever for shifting the elevator to align the matrices with the mold, a relatively deep spring operatively connecting the said lever with the elevator, means for adjusting the tension of said spring, a cam for operating the lever and having a heel 110 when operatively engaged with the lever to shift the elevator to bring the matrices in alignment with the mold, and a member detachably engaged with the heel to increase 115 the throw of the heel to thereby add lift for alignment.

In testimony whereof we hereunto affix our signatures.

WILLIAM EDGAR ZOLMAN.
ANDREW W. BRADSHAW.
